DIRECT COUPLED AMPLIFIER

Barend Albert Jan ten Brink, The Hague, Netherlands, assignor to Heinrich Willem Karel De Brey, The Hague, Netherlands

Application July 3, 1931, Serial No. 548,664
In the Netherlands July 11, 1930

6 Claims. (Cl. 179—171)

The invention relates to electrical amplifiers and more particularly to direct-coupled electrical amplifiers or so-called direct-current amplifiers, in which a resistance is employed for the coupling of two amplifying valves which resistance is not only connected with the anode of the first valve but also on the same side with the grid of the following valve.

By the expression "feed device" as hereafter used is meant a source of current from which tappings can be taken only by means of a resistance connected in parallel with it. Such a resistance, however, will invariably introduce the drift effect referred to hereinafter on page 2, paragraph 2 of the specification. The great advantage of the invention is that although feed devices are used for the current supply the circuit arrangement of these feed devices is such that resistances for tapping of suitable working voltage for the individual tubes are not necessary.

According to the invention, in a direct-coupled electrical amplifier consisting of two valves, there is available a considerably higher (preferably twice or more times) voltage for the feeding of the first valve than for the feeding of the second valve. In addition to the usual feed device, there may be provided an additional feed device which supplies no energy to the second valve but whose voltage is added, for the first valve, to that of the usual feed device.

In order that the invention may be clearly understood and readily carried into effect, it will now be described more fully with reference to the accompanying drawing, in which:—

Figure 1 illustrates diagrammatically a known circuit arrangement of a direct-coupled electrical amplifier, and

Figures 2 and 3 illustrate diagrammatically two examples of an arrangement of direct-coupled amplifier in accordance with the invention.

In electrical amplifiers of the kind above referred to, the grid of the second valve obviously has the same voltage as the anode of the first valve. This grid, therefore, compared with the corresponding cathode, should be negative, this being necessary for distortionless amplification, so that the cathode of the second valve compared with the cathode of the first valve must have a still higher positive voltage than the grid of the second valve. This has led to the choosing in known circuits of feed voltages for the anode circuits of both valves in the manner diagrammatically illustrated in Figure 1. In that figure two valves I and II are represented which are fed from a feed device connected with the terminals

A, A and generating a total voltage V which, by means of a resistance R, can be tapped off at different points. 1 is the coupling resistance between the two valves, and the terminals of the load circuit of the second valve are represented by 2. By virtue of the points of connection of the separate anode and cathode conductors to the resistance R of the anode feed device, it is seen that essentially the same feed voltages are supplied to the two valves, which, however, have a different level. The feed voltage of the valve II lies as a whole higher than the feed voltage of the valve I. The filament of the valve II has, compared with the lower terminal A, such a positive voltage that the grid of the valve II receives the desired negative grid bias compared to the corresponding cathode.

In the above-described known circuit, neither of the two valves utilizes the whole of the voltage generated between the terminals A, A, a circumstance which is disadvantageous for various reasons. There is a limitation of the grid amplitude which is capable of amplification without distortion, and moreover, the second valve is not in a position to give its maximum output. Further, the action of the first valve which is already encroached upon as a result of the provision of the coupling resistance 1 (drop of potential), is still further reduced so that the advantage of the direct coupling for distortionless amplification is not made full use of.

By means of the invention, the removal of these disadvantages is made possible. The basis of the invention is formed by the recognition that there are various advantages in supplying to the first valve a considerably higher (e. g. twice or several times higher) voltage than to the second valve. As regards the first valve, there is clearly a part of the feed voltage lost in the coupling resistance and this part is greater the greater is chosen the coupling resistance with the object of obtaining a higher amplification.

As now the feed voltage of the first valve is considerably raised, the significance of this loss is reduced not only for the reason that the valve itself has at its disposal a sufficient voltage in order to be able to work under favourable conditions, but there moreover arises the possibility of employing a coupling element whose resistance is large compared with the internal resistance of the valve and which is so suited to this valve that the distortionless amplification attained reaches a very much higher value than in known circuits. The arrangement according to the invention is of far-reaching significance, especially

if the first amplification stage is equipped with a screened grid valve, which in general has a considerably higher internal resistance than a three-electrode valve.

5 The raising of the feed voltage of the first valve is attained, according to the invention, in that, besides the usual feed device, there is employed a feed device whose voltage, for the first valve, is added to that of the existing feed device 10 and which, however, supplies no energy to the second valve. There is thereby the further possibility of employing the whole voltage of the usual feed device for supplying the second valve, and thereby to amplify without distortion a greater 15 grid amplitude and to obtain a greater output energy.

Another and not less important advantage of the above described method of feeding is present in that the drift effect which makes itself so unpleasantly noticeable with direct-coupled amplifiers and which has up to the present stood in the way of the practical application of such amplifiers, is completely removed. In the circuit arrangement according to Figure 1, there is the 20 difficulty that the circuits of the two valves mutually react on account of their connection with the same feed device so that the stability of the amplifier as a whole is endangered and in consequence distortionless amplification is quite impossible. With nothing to apparently disturb the state of equilibrium of the system, the plate current of the last tube begins to drift until it is completely out of line and, of course the tube is entirely off the correct portion of its operating 25 characteristic. This difficulty is either altogether unavoidable or avoidable only with the aid of special compensating circuits. On the other hand, with the arrangement according to the invention, in which use is made of an additional 30 anode feed device which only supplies energy to the first but not to the second valve, this difficulty no longer arises. The arrangement is stable without more ado.

The second additional feed device, as it feeds 45 only the first valve, need only give a small output. In a direct-current amplifier the first valve serves mainly only for voltage amplification, and in consequence of this it takes a much smaller current than the second valve which has to supply the consumption circuit (for example, a loud 50 speaker) with energy.

Consequently, even disregarding the remaining 55 advantages, the efficiency of the amplifying arrangement according to the invention is considerably better than that of known circuits in which it is endeavoured to obtain a better amplification by raising the feed voltage. In the latter case it is, of course, necessary to dimension the whole feed device according to the current taken by the second valve. There is thereby occasioned a high 60 continuous loss of energy. According to the invention, a considerable advance is therefore obtained not only as regards amplification but also in the economy of the whole arrangement with small costs.

65 Referring now to Figures 2 and 3 of the accompanying drawing, Figure 2 represents a direct-current amplifier consisting of two valves with an indirectly-heated screen-grid valve I, which is connected by means of a coupling resistance 1 with a three-electrode valve II. 15 are the input terminals, and 17 the output terminals of the amplifier which are connected to the arrangement through a transformer 16.

70 For feeding the two valves there are provided

according to the invention, two feed devices A and B (which are surrounded with dotted lines) and each assumed to consist of a transformer fed from the mains, with an appropriate rectifier. The feed device A consists of the transformer 4 and a rectifier 6, the feed device B of the transformer 3 and the rectifier 5. The two feed devices are connected with one another at the point 2 and are connected to the two valves in such a manner that there is fed to the anode circuit of the valve I the sum of the two voltages, but to the anode circuit of the valve 2, only the voltage of the feed device B. Reckoned from the point 2 outwards, the two feed devices therefore generate 10 opposed voltages.

15 A smoothing circuit is connected with the feed device A which is formed by a resistance 11 and two condensers 12 and 12'. Consequently, the point D possesses, compared with the point C, a smooth (that is free from all alternating-current components) positive direct voltage. The feeding arrangement B acts in conjunction with two smoothing circuits of which one consists of the choke 7 and two condensers 8 and 8' and the other of two resistances 9 and 9' and two condensers 10 and 10'. The direct voltage of the point E is therefore again positive compared with that of the point D.

20 From Figure 2 it is seen that the one end of the coupling resistance 1 in the anode circuit of the valve I is connected with the point E so that between this point E and the cathode side of the valve I there is provided a feed voltage corresponding to the sum of the voltages of the two feed devices A and B. The resistance 13 and the 25 condenser 14 connected in parallel with it in the cathode connecting conductor of the valve I serve in known manner to convey automatically to the grid of this valve the desired negative grid bias.

30 Regarding the valve II, it is seen that this receives between the cathode and the output transformer 16, a feed voltage afforded only and determined by the feed device B. The anode conductor 18 is connected with the output circuit of the feed device B behind the first smoothing circuit 45 7, 8, 8'; the smoothing circuit 9, 9', 10, 10' influences, therefore, only the anode current of the valve I. The reason of this connection will be more fully explained below.

35 On consideration of the voltage distribution over the whole amplifier arrangement, it is seen that the cathode of the valve II has a positive voltage compared with that of the valve I which is approximately equal to the voltage of the feed device A.

40 The negative grid bias of the valve II is obtained by virtue of the fact that in the coupling resistance 1 there is produced such a drop of potential that the potential of the anode of the valve I is somewhat lower than that of the cathode of the valve II or that of the point of connection 2 of the two feed devices A and B. The screen grid of the valve I is only fed from the feed device A and assumes through the drop of potential in the resistance 19 a potential which is again somewhat lower than the anode potential of this valve.

45 In the above-mentioned circuit the valve I as well as the valve II receives a feed voltage which ensures an optimum for the amplification under the special circumstances determined for these 50 valves.

55 As the first valve only takes a very small current from the series connection of the two feed devices, in consequence of the coupling resistance 1, the feed device A is only very lightly loaded; it, 70 75

therefore, needs to be designed only for a small output which is advantageous to the efficiency of the whole arrangement. Further, the direct voltage afforded by the feed device A will be approximately equal to the peak value of the voltage generated in the secondary winding of the transformer 3. By means of this high voltage, one is in a position to adapt the coupling resistance 1 in an appropriate manner to the valve I.

10 As already mentioned, there thus occurs a high amplification, while the valve, however, receives a sufficient voltage to enable it to work on the rectilinear part of its characteristic curve where the permissible amplitude of the control voltage 15 has a high value. On the other hand, the whole voltage of the more powerfully designed feed device B stands at the disposal of the valve II so that the characteristic properties of this valve can also be completely made use of.

20 Obviously it is not absolutely necessary to choose a screened grid valve for the valve I and for the valve II a three-electrode valve. Other kinds of valves may be employed with equal success.

25 The feed device B is provided with two smoothing circuits for the reason that practice has shown that the feed current of the valve I should be usually smoothed more than that of the valve II. This is attained in that the usual smoothing circuit 7, 8, 8' of the feed arrangement for the 30 end valve II is arranged with a second smoothing circuit 9, 9', 10, 10'. As, however, is to be seen from Figure 3, the connecting in series of the two smoothing circuits is not absolutely necessary.

35 Figure 3 represents a somewhat different circuit arrangement of the direct-coupled amplifier according to the invention in which a simplification has been provided in the formation of the two feed devices, whereby the cost of the arrangement is reduced. The operation otherwise agrees completely with that of the arrangement according to Figure 2.

40 In the arrangement of Figure 3, the two rectifiers 5 and 6 are connected with the secondary winding of the same transformer 4. Thus, therefore, the two feed devices A and B are, as it were, connected with one another, whereby one transformer is saved. The low loading of the rectifier 5 for the feeding of the valve I makes this change 45 possible without further ado. In order to be able to regulate within certain limits the voltage afforded by this rectifier, a tapping-off switch is provided between the rectifier and the secondary winding of the transformer 4.

50 The circuit arrangement according to Figure 3 deviates further from that according to Figure 2 in that the two smoothing circuits of the part A of the combined feed device are not connected in series but in parallel. The anode current of the valve II is only influenced by the choke 7 and the condensers 8, 8', the current for the feeding of the valve I on the contrary by the smoothing circuit 9, 9', 10, 10' in conjunction with the condenser 8. This arrangement has the advantage that the drop of potential arising from the anode current of the valve II in the choke 7 is not subtracted from the feed voltage intended for the valve I.

55 In the circuits according to the invention, it is advantageous to connect the point of junction of the two feed current devices to earth. The advantage is thus obtained that the maximum voltage with respect to earth is reduced. This choice of earth connection is, however, not ab-

solutely necessary. The earth connection could be made in the usual manner on the cathode of the valve I.

60 If the point of connection of the two feed devices is earthed, it is obviously necessary to insulate the input circuit of the amplifier from the amplifier stages which may precede it, or from other devices, and this may be brought about, for example, by the use of an input transformer.

10 The supply to the cathodes of the amplifier or rectifier valves is not represented either in Figure 2 or in Figure 3 as this forms no part of the invention.

15 It is to be understood that the valve I may act not only as amplifier but also as detector.

Also it is obvious that the above-described circuit arrangement, insofar as it concerns the rectifier, may be made double-acting (full wave rectification). Usually such an arrangement will 20 only come into consideration with very large outputs. As a result of the very high voltages with which the arrangement according to the invention works compared with known circuits, the smoothing condensers employed in most cases 25 completely suffice to bring about a sufficient smoothing with simple rectifiers also.

What I claim is:—

1. A direct coupled electric amplifier comprising a first valve and a second valve, a high voltage feed device comprising a rectifier and having its terminals connected with the cathode of the first valve and the anodes of both valves respectively, an additional feed device comprising a rectifier and having its terminals connected with the cathode of the first valve and the cathode of the second valve respectively, said additional feed device having a connection for the anode of the first valve through the high voltage feed device.

2. An amplifier according to claim 1, in which the point of connection of the two feed devices is connected to the cathode of the second valve, the other terminals of the two feed devices are respectively connected with the anode conductors of the two valves and with the cathode conductor of the first valve, and smoothing circuits interposed in each of the connections from said other terminals.

3. A direct-coupled electrical amplifier comprising two valves, a high voltage feed device, an additional feed device, a connection between the two devices, the common point of connection between the two devices being connected to the cathode of one of the valves, the opposite terminal of the high voltage feed device being connected to the anodes of the two valves, the opposite terminal of the additional feed device being connected to the cathode of the other valve, and smoothing circuits interposed in the connections from said opposite terminals.

4. Amplifier according to claim 1, in which the point of connection of the two feed devices is connected to the cathode of the second valve, the opposite terminal of the one feed device is connected to the anode conductors of the two valves, the opposite terminal of the other feed device is connected with the cathode conductor of the first valve, and the feed device providing the anode conductors of the two valves with current is provided with two smoothing circuits, of which one is interposed in the connection between said feed device and the anode conductor of the first valve, and the other is interposed in the connection between said feed device and the

anode conductor of the second valve or the anode conductors of both valves.

5. A direct-coupled electrical amplifier according to claim 3 in which the first valve has a screen grid connected through a resistance with the point of connection of the two feed devices.

6. A direct coupled electrical amplifier according to claim 3 in which the high voltage feed

device and the additional feed device comprise a common secondary winding of a feed transformer and two separate rectifiers, one end of said winding being connected to the cathode of one of the valves and other points of said winding being connected to the anode of one rectifier and to the cathode of the other rectifier respectively.

5 BAREND ALBERT JAN TEN BRINK.
